HAND GRIP FOR A BUST DEVELOPER

Jack Vincent Feather, 11293 Kerrigan Drive,
Oakland, Calif. 94605

Continuation-in-part of design application Ser. No.
8,940, June 27, 1967. This application Feb. 23,
1968, Ser. No. 11,037

Term of patent 14 years

U.S. Cl. D83—1
Int. Cl. D24—99

Fig. 1.

Fig. 2.

Fig. 3.

FIG. 4.FIGURE 1 is a top plan view of a hand grip for a bust developer showing my new design;

FIGURE 2 is a side elevation thereof;

FIGURE 3 is a front elevation thereof;

FIGURE 4 is a bottom view thereof.

The dominant features of my design reside in the portions shown in full lines.

This is a continuation-in-part of design application Ser. No. D-8940, filed June 27, 1967, and now abandoned.

I claim:

The ornamental design for a hand grip for a bust developer, shown and described.
